UNITED STATES PATENT OFFICE.

GUSTAV UNGER, OF HANNOVER, GERMANY.

RIGID AIRSHIP.

Application filed January 14, 1924. Serial No. 686,144.

To all whom it may concern:

Be it known that I, GUSTAV UNGER, engineer, a citizen of the German Republic, and resident of Hannover, Germany, have invented certain new and useful Improvements in Rigid Airships, of which the following is a specification.

My invention relates to air-ships of the kind known as rigid air-ships; more especially it relates to the frame-work thereof, and the object of my invention is to improve the frame-work in such a way as to make it apt to answer all requirements as regards breaking strain, saving in weight, swimming capacity on water, slight resistance to air, and the like.

According to my invention, the body of the rigid air-ship is composed of a channel-forming central longitudinal frame-work forming a kind of back-bone or spine for the air-ship, and of cross-shaped transverse members or trellis-work girders connected with annular double circumferential body-members determining, in connection with wires connecting said latter members with each other, the outer shape of the air-ship. The thus produced sector-shaped compartments of the frame-work form cells to house the gas bags which, enclosed by the staying or stiffening wires of the inner circumferential body-members, form, in their entirety, the carrying body of the air-ship which is either torpedo-shaped or roll-shaped, the gas-bags being correspondingly arranged in the longitudinal direction of the body, as well as side by side horizontally and vertically, as will more fully appear from the detailed part of this specification.

Some horizontal cross-members are elongated laterally beyond the circumference of the frame-work, as are also some of the vertical cross-members thereof, but these latter parts are elongated only vertically downwards, not also upwards, whereas the horizontal parts are elongated to both sides. These lateral elongations form carriers for the motors and the propellers, whereas the downwardly elongated parts of the vertical members form carrying parts for the suspended structure supporting the cabins and the like.

My invention is illustrated, by way of example, in the accompanying drawing, in which Figure 1—1^a is partly a side-view and partly a vertical section of my improved rigid air-ship; Figure 2 is a cross-section of

the body-structure near the head of the air-ship, in the plane 5—6 of Figure 1; Figure 3 is a cross-section of a middle part of the air-ship, in the plane 7—8 of Figure 1, and Figure 4 is a plan of the middle part of the air-ship, a part of the envelope being removed in order to show the structural work, and the propeller, the motor on one side being omitted.

The central part of the frame-work consists of channel-forming longitudinal trellis-work *a* connected with cross-shaped members consisting of horizontal parts *b*² and of vertical parts *b*¹. The outer ends of these members are connected with annular double circumferential members *c* *c*¹, *c*¹ being the inner parts, *c* the outer parts thereof. These annular members are connected with each other, lengthwise of the air-ship, by parallel horizontal wires *f* which can yield in a certain measure in the case of the air-ship setting somewhat hard on the ground. There are formed in this way quadrant-shaped compartments *g* which receive the gas-bags. The bags in the upper compartments may be connected by hoses with the bags in the lower compartments in order to render possible a compensation of the contents of the bags in comparatively high altitudes. The filled bags contact at their inner surfaces with diagonal wires *k* extending from the central trellis-work to that at the outer sides of the body, and at their other sides with the parallel wires *f* extending from any of the annular circumferential structural members to its two neighbouring ones.

Owing to the formation of quadrant-shaped compartments for the reception of the gas-bags, or, in other words, owing to the arrangement of quadrant-shaped gas-bags in the longitudinal direction of the ship, as well as side by side horizontally and vertically, the gas-pressure in the upper bags acts on the annular circumferential structural body-members standing vertically relatively thereto, and the gas-pressure in the lower bags which act independently of the upper ones acts on the horizontal parts of the cross-shaped structural members, whereby a good buoyancy is warranted. Besides, owing to the gas in the upper and the lower bags pressing also on the vertical parts of said cross-shaped structural body-members, the vertical walls of the compartments are anchored relatively to the neigh-

houring parts of the body structure whereby the stability of the entire structure is considerably improved.

The wires *f* connecting the parts *c* of the 5 annular circumferential structural members *c c'* receive and carry the envelope *l*. The outer surface of the air-ship is, practically, completely smooth, there being no elevations and no cavities or the like, so that the 10 resistance to air is the smallest possible and an increased speed is possible.

The lower elongations *b*¹ of the members *b* carry the suspended structure *i* carrying in its turn the cabins. There also are partition 15 structures *h* connecting the suspended structure *i* with the lower longitudinal trellis-work girder of the body. The horizontal elongations *b*² of the members *b*² carry the propellers *j* and their motors *j'*. Owing to 20 the stability of the air-ship being very great, the propellers on its two sides may work simultaneously in opposite directions whereby quick turning is greatly facilitated.

I claim:

25 1. A rigid air-ship, comprising, in combination, a channel-forming central longitudinal structure; cross-shaped structures connected at their centre parts with said longitudinal structures; double annular circumferential structures connected with the outer ends of said cross-shaped structures, one annulus of each pair of these structures being located inside the other one; lateral outer structures projecting beyond some of 30 said circumferential structures and forming elongations of some of the horizontal members of said cross-shaped structures and being adapted to carry the propellers and the motors; propellers and motors attached to, and carried by, said elongations; downwardly 35 extending structures projecting also beyond some of said circumferential structures and forming elongations of some of the vertical members of said cross-shaped structures and being adapted to carry the structure supporting the cabins; 40 projecting also beyond some of said circumferential structures and forming elongations of some of the vertical members of said cross-shaped structures and being adapted to carry the structure supporting the cabins;

wires connecting the inner annuli of the said 45 circumferential structures with each other, and wires connecting their outer annuli with each other; gas-bags housed in the gas-cell forming compartments formed by, and located between, said structural parts of the 50 air-ship body, except said outer wires; and an envelope enclosing these parts and being supported also by the said outer wires, substantially as set forth.

2. A rigid air-ship, comprising, in combination, a channel-forming central longitudinal structure; cross-shaped structures connected at their centre parts with said longitudinal structures; double annular circumferential structure connected with the outer 60 ends of said cross-shaped structures, one annulus of each pair of these structures being located inside the other one; lateral outer structures projecting beyond some of said circumferential structures and forming elongations of some of the horizontal members 65 of said cross-shaped structures and being adapted to carry the propellers and the motors; propellers and motors attached to, and carried by, said elongations; downwardly 70 extending structures projecting also beyond some of said circumferential structures and forming elongations of some of the vertical members of said cross-shaped structures and being adapted to carry the structure supporting the cabins; a cabin-carrying structure suspended from these elongations, and cabins on this structure; wires connecting the said circumferential structures with each other; gas bags housed in the gas-cell forming compartments formed by, and located between, all said structural parts of the air-ship body, and an envelope enclosing these 75 parts, substantially as set forth.

In witness whereof I have hereunto set my 80 hand.

GUSTAV UNGER.
